UNITED STATES PATENT OFFICE.

JOHN E. LUCAS, OF BROCKTON, MASSACHUSETTS, ASSIGNOR TO FREDERICK R. WOODWARD, OF NEWTON, MASSACHUSETTS.

MACHINE FOR MAKING WELTS.

1,278,956.

Specification of Letters Patent. Patented Sept. 17, 1918.

Application filed November 24, 1917. Serial No. 204,127.

To all whom it may concern:

Be it known that I, JOHN E. LUCAS, a citizen of the United States of America, and a resident of Brockton, in the county of 5 Plymouth and Commonwealth of Massachusetts, have invented certain new and useful Improvements in Machines for Making Welts, of which the following is a specification.

10 This invention relates to welt machines and has for its object the production of a machine of this character in which welts may be formed from plastic sheets of material and be reinforced simultaneously with 15 strips of woven material.

The invention consists in two revoluble rolls coacting with each other and provided with peripheral depressions and projections coöperating to cut from a sheet of material 20 a strip and form therein a stitch receiving groove, the usual bevel edge and a plurality of lateral indentations to give a finished appearance to said welt when in the completed shoe.

25 The invention further consists in certain novel features of construction and arrangement of parts which will be fully understood by reference to the description of the drawings and to the claims hereinafter given.

30 For the purpose of illustrating the invention one preferred form thereof is illustrated in the drawings, this form having been found to give satisfactory and reliable results, although it is to be understood that 35 the various instrumentalities of which the invention consists can be variously arranged and organized and that the invention is not limited to the precise arrangement and organization of these instrumentalities as 40 herein shown and described, except as required by the scope of the appended claims.

Of the drawings:

Figure 1 represents an elevation of a machine embodying the principles of the present invention, a portion thereof being shown in section.

Fig. 2 represents an end view of the same, a portion of the lower roll being shown in section.

50 Fig. 3 represents a plan of a welt formed on said machine.

Fig. 4 represents an inverted plan of the same.

Fig. 5 represents a transverse section of the same, and

Fig. 6 represents a similar section of a welt formed without the strip of reinforcing material.

Similar characters designate like parts throughout the several figures of the drawings.

In the drawings, 10 is a frame having a shaft 11 revolvably mounted in bearings therein. One end of the shaft 11 has secured thereto the fast and loose pulleys 12 and 13 and intermediate the loose pulley 13 and the frame 10 is a gear 14 meshing with a gear 15 secured to a revoluble shaft 16 mounted in bearings in blocks 17 and 18. The blocks 17 and 18 are adapted to be moved vertically in slots 19 in the frame 10.

The revoluble shaft 11 has secured thereto a roll 20 coacting with a roll 21 secured to and revoluble with the shaft 16. When power is applied to the fast pulley 12 the 75 shafts 11 and 16 are rotated simultaneously. The roll 21 is adapted to be moved toward the roll 20 by means of the adjusting member 22 threaded to the frame 10.

The roll 20 is provided with peripheral 80 flanges 23 and 24 between which is positioned a portion of the roll 21, the outer face of said roll 21 bearing against the inner faces of the flanges 23 and 24.

Adjacent to the flange 24 is an outwardly 85 inclined peripheral portion 25 and intermediate this inclined portion 25 and the flange 20 is a row of lateral projections 26. The roll 21 is provided with a continuous annular bead 27 which is in a plane intermediate 90 the inclined portion 25 and the row of lateral projections 26.

Secured to the frame 10 is a guide member 27 through which a strip of woven material 28 is fed to the roll 21. When the machine is in operation a sheet of semi-plastic material 29, such as rubber, is placed upon the roll 20 with its edge abutting the inner face of the flange 24.

As the sheet of material is fed between 100 the rolls 20-21 a strip 32 will be cut therefrom by the sharp corners 30 and 31 of the

rolls 21 and 20. As this strip is fed between the rolls 20 and 21 a row of indentations 33 will be pressed into the under side of the strip and a beveled portion 34 formed near one edge thereof, as shown in Figs. 4 to 6 inclusive.

As the strip 32 is fed between the rolls 20 and 21 the bead 27 will form a stitch receiving groove 35 in the upper face of said strip. 10 If desired, the strip may be formed wholly of semi-plastic material as shown in section in Fig. 6 of the drawings, but preferably during the formation of the strip the strip of woven material 28 is fed around the roll 21 and pressed into the upper surface of the strip 32, as shown in Figs. 1, 2, 3, and 5.

As the strip 32 is delivered from the machine, it may be vulcanized or otherwise treated so as to prepare it for commercial 20 use. Obviously any coloring matter may be used in the plastic material as it is cut into the strip to adapt it for use in the manufacture of shoes of different colors.

The machine is particularly adapted for 25 use in manufacturing the rubber welts for shoes for which Letters Patent No. 1,173,287 were issued to me February 29, 1916. Any desired pressure upon the strip may be secured by adjusting the threaded member 22 bearing upon the block 18.

By means of this construction welts may be formed without the use of skiving knives or other cutting instruments for forming 30 a stitch receiving groove.

35 By means of this machine during the manufacture of the strip the row of indentations 33 may be simultaneously formed, thus dispensing with the necessity of forming these indentations after the shoe is manufactured, as is now the usual practice.

40 Heretofore in the manufacture of welts from pieces of leather the various pieces are lapped and cemented together and then skived to give an even thickness thereto. 45 They are then rolled and subsequently cut into strips of the desired width. Then these strips are grooved and beveled.

There are five different operations to 50 make a welt while in the present machine the welt is completed in one operation on a single machine.

The strips formed on applicant's machine are made in long lengths of from 60 to 75 55 feet in length, making it possible to cut them up into shorter lengths, each of which shorter lengths is integral and has no lapped portion.

In the leather welts there is liable to be 60 considerable waste if the lapped portions are cut out and if not cut out they often become separated on account of the imperfect cementing.

These objections are wholly overcome by 65 the manufacture of the welts from plastic material on a machine as herein described.

It is believed that the operation and many advantages of this invention will be fully understood from the foregoing description.

Having thus described my invention, I claim:

1. In a device of the class described, the combination of two revoluble rolls, one of which has an annular depression to receive a portion of the periphery of the other roll, the opposite ends of which contact with the side walls of said depression, and one of which is provided on its periphery with a continuous bead. 70

2. In a device of the class described, the combination of two revoluble rolls, one of which has an annular depression to receive a portion of the periphery of the other roll, the outer end of which contacts with a side wall of said depression, thereby in the rotation of said rolls producing a shearing 80 action on the material fed thereto, and one of which is provided on its periphery with a row of unbroken lateral projections parallel with the axis of said roll. 85

3. In a device of the class described, the combination of two revoluble rolls, one of which has an annular depression to receive a portion of the periphery of the other roll, the opposite ends of which contact with the side walls of said depression, and one of 90 which is provided on its periphery with a continuous row of lateral projections and a parallel outwardly inclined portion. 95

4. In a device of the class described, the combination of a revoluble roll having peripheral flanges and a row of lateral projections intermediate said flanges; and another roll adapted to revolve with a portion of its periphery between said flanges and having a continuous peripheral bead near 100 one edge thereof equidistant throughout its length from the ends of said roll. 105

5. In a device of the class described, the combination of a revoluble roll having peripheral flanges and a row of unbroken lateral projections intermediate said flanges parallel with the axis of said roll; and another roll adapted to revolve with a portion of its periphery between said flanges and having a continuous peripheral bead near 110 one edge thereof and offset from said row of projections. 115

6. In a device of the class described, the combination of a revoluble roll having peripheral flanges and a row of lateral projections intermediate said flanges and a continuous peripheral portion inclined outwardly toward one of said flanges; and another roll adapted to revolve with a portion of its periphery between said flanges and having a continuous peripheral bead near 120 one edge thereof. 125

7. In a device of the class described, the combination of a revoluble roll having peripheral flanges and a row of lateral pro- 130

jections intermediate said flanges and a continuous peripheral portion inclined outwardly toward one of said flanges; and another roll adapted to revolve with a portion of its periphery between said flanges and having a continuous peripheral bead near one edge thereof in a plane intermediate said row of projections and said inclined portion.

10. 8. In a device of the class described, the combination of a revoluble roll having peripheral flanges and a row of lateral projections intermediate said flanges and a continuous peripheral portion inclined outwardly toward one of said flanges; another roll adapted to revolve with a portion of its periphery between said flanges and having a continuous peripheral bead near one edge thereof; and means for varying the space between the peripheries of said rolls.

9. In a device of the class described, the combination of a revoluble roll having peripheral flanges and a row of lateral projections intermediate said flanges; another

roll adapted to revolve with a portion of its periphery between said flanges and having a continuous peripheral bead near one edge thereof; and means for guiding a strip of reinforcing material to and beneath the upper roll, said strip being of considerably less thickness than the depth of the space between said rolls.

10. In a device of the class described, the combination of a revoluble roll having peripheral flanges and a row of lateral unbroken projections intermediate said flanges, said projections being parallel to the axis of said roll; another roll adapted to revolve with a portion of its periphery between said flanges and having a continuous peripheral bead near one edge thereof; and means for rotating said rolls simultaneously.

Signed by me at 4 Post Office Sq., Boston, Mass., this 28th day of June, 1917.

JOHN E. LUCAS.
